UNITED STATES PATENT OFFICE.

WILLIAM REDFORD MULOCK, OF WINNIPEG, MANITOBA, CANADA.

TOY SHELL.

1,247,989.

Specification of Letters Patent.

Patented Nov. 27, 1917.

Application filed May 17, 1917. Serial No. 169,358.

To all whom it may concern:

Be it known that I, WILLIAM REDFORD MULOCK, of the city of Winnipeg, in the Province of Manitoba, Canada, have invented certain new and useful Improvements in Toy Shells, of which the following is the specification.

The invention relates to improvements in toy shells and the object of the invention is to provide an amusement appliance in the nature of a shell formed from sections which can be put together and interiorly locked so that it cannot be opened by exterior hand manipulation and which when dropped will be set off, so to speak, to fly apart, producing at the same time a sharp report thereby giving the effect of a shell bursting under an interior explosion.

With the above object in view the invention consists essentially in a shell formed from a plurality of assembled sections, means for interiorly locking the shell sections in place, said means being adapted to be released by impact of the shell with an object and means for effecting an explosion simultaneously with the shell striking the object, the parts being arranged and constructed as hereinafter more particularly described and later pointed out in the appended claims, reference being had to the accompanying drawing in which:

Figure 1 represents a side view of the complete shell and as it appears in what might be termed the closed position.

Fig. 2 represents a longitudinal sectional view centrally through the shell.

Fig. 3 represents a side view of the shifting member.

Fig. 4 represents an enlarged detailed vertical sectional view through the shell, the section being taken in the plane denoted by the line X—X' Fig. 1 and looking toward the left hand end.

Fig. 5 represents an enlarged detailed vertical sectional view through the shell, the section being taken in the plane denoted by the line Y—Y' Fig. 1 and looking toward the right hand end.

In the drawing like characters of reference indicate corresponding parts in the several figures.

1 and 2 represent the nose and butt ends

of the shell which are spaced a determined distance apart and are securely fastened to the opposite ends of a central guide shaft 3. 55

The nose end of the shell is bored to receive a weight 4, the object of which is to make the nose end of the shell heavy so that when the said shell is dropped from a height it will naturally turn nose down. 60 While the weight has been shown embedded in the nose it will be readily understood that the nose itself could be made of material heavier than the butt to effect the same purpose, or the end made heavier in any 65 other way.

On the shaft I mount slidably a shifting member 6 which presents a disk like head 7 carrying an extending cylindrical skirt or flange 8 which is of the same external di- 70

ameter as the head. Toward the nose end of the shell the shaft is slotted as indicated at 9 and the slot receives a retarding spring 10 secured to the shaft and engageable with the shifting member and adapted to retard the sliding movement of the shifting member in a more or less central position on the shaft. 75

Around the shaft and bearing on the butt and nose and on the shifting member I build up the wall of the shell which is formed from sets of, what might be termed, head and butt sections 11 and 12 which are approximately equal in length and span between the head and butt ends of the shell. 85 The sections 11, of which in the present instance there are six in number, (this number can be increased or decreased as desired) are all identical in form and each has the ends thereof oppositely tapered as indicated at 11' and 11'', the tapering ends 11' being designed when the said sections are assembled to enter a more or less V-shaped groove 13 provided in the rear of the nose 1. This groove is a continuous one having the inner side thereof contained in a circle of the same diameter as the diameter of the disk 7 so that when the said sections are placed in position they entirely close around the front end of the shell with their edges meeting 95 and their outer faces flush with the nose. 100

The sections 12 are the same in number as the sections 11 and they are adapted to inclose the rear end of the shell and they have

their ends beveled in the same direction as indicated at 12' and 12" so that when assembled their forward ends overlie the ends 11" of the front sections.

5 The rear ends 12" of the sections 12 are adapted to enter a substantially V-shaped continuous groove 14 formed in the butt 2 of the shell and the inner side of this groove is contained in a circle having a diameter 10 equal to the diameter of the disk.

From the above disclosure it will be apparent that when all the sections are assembled with the ends 11' in the grooves 13, the ends 12" in the grooves 14 and the ends 15 12' overlapping the ends 11" and bearing on the shifting member the whole appliance presents a shell like shape.

In carrying out my invention it is necessary that the sections be locked interiorly 20 so that they cannot be opened from the outside by hand manipulation and to this end I have provided the parts now described which coöperate with the shifting member to lock the sections.

25 Each of the butt sections 12 is provided with a spring 15 which is permanently secured in any suitable way such as by riveting as shown at 16 to the section, which spring passes lengthwise of the section and 30 has the rear end inturned and riding on the shaft and the forward end deflected slightly inwardly and provided with a rounded tip 17. The arrangement of the springs is such that when the rear sections 35 are assembled there is a tension built up in the rear ends of the spring which is utilized to fling out the butt sections when the appliance is unlocked as later described.

The nose end of the shell is fitted with a 40 striking plate 18 which carries a spring catch 19 underneath which I place a percussion cap 20. The above completes the description of the parts.

The appliance is used in the following way 45 considering the sections have been removed.

One first slides the shifting member to the position shown approximately in dotted outline in Fig. 2, in which position it will be seen it is retarded against sliding by the 50 spring 10, and then inserts the percussion cap under the catch 19. He then assembles the sections 11 and afterward the sections 12. Then, holding these all closed, he turns the shell nose up and strikes the butt end 55 sharply against any solid object such as a floor or table, which action causes the shifting member to move toward the butt 2.

In passing in this direction it will be readily apparent that the skirt of the said member 60 will be passed around the forward ends of the springs and will be more or less jammed in the position shown in full outline in Fig. 2. By this movement the sections are locked closed around the shifting member and ob-

viously the shell cannot be opened from the exterior by hand manipulation.

At this point it is to be observed that as there are quite a number of sections one is given more or less trouble in assembling them, particularly in view of the fact that 70 they are not held in any way, only by the hand until locked as above explained.

After the shell has been locked it can be exploded so to speak by holding it in an elevated position, above a stationary object 75 and allowing it to drop. As it drops the nose end will turn down and will strike the object. In striking the object the impact causes the shifting member to move toward the nose end of the shell with the result that the forward ends of the springs are released from the skirt and free the sections 12 which are flung out by the action of the springs 15. Immediately the sections 12 are released the sections 11 are free and 80 they scatter as affected by the jar. Simultaneously with the shell striking the object the cap explodes for the reason that it is struck by the then falling sliding member.

Obviously from the above disclosure the 90 complete effect of the shell when dropped is one which is very realistic owing to the fact that the dropped shell not only scatters but also produces an explosion.

While I have described the invention in 95 detail it will be readily understood that various changes could be readily made in the construction without in the least departing from the spirit of the invention and as covered by the appended claims.

What I claim as my invention is:

1. A locked sectional toy shell adapted to be unlocked upon impact with an object.

2. An assembled sectional interiorly locked toy shell adapted to be unlocked by 105 impact with an object.

3. A sectional toy shell and means for interiorly locking the assembled sections, said means being constructed to unlock upon impact of the shell with an object.

4. A toy shell formed from assembled sections, means for interiorly locking the assembled sections, said locking means being adapted to unlock upon the impact of the shell with an object and means for effecting 115 an audible explosion coincident with the striking of the shell with the object.

5. A toy shell formed from assembled locked sections and adapted, when dropped to strike an object, to unlock and scatter the 120 sections and simultaneously effect an audible explosion.

6. A toy shell having a nose and a butt end and formed from assembled sections and means for interiorly locking the sections closed, said locking means being constructed to effect the locking of the sections by the striking of the shell butt against an object 125

and to effect the unlocking of the shell sections by the striking of the shell nose against an object.

7. A toy shell having a nose and a butt end and formed from assembled sections and means for interiorly locking the sections closed, said locking means being constructed to effect the locking of the sections by the striking of the shell butt against an object 10 and to effect the unlocking of the shell sections by the striking of the shell nose against an object and means for effecting an audible explosion coincident with the unlocking of the sections.

15. 8. A toy shell comprising, connected nose and butt ends, grouped body sections inclosing the sides of the shell between the nose and butt ends, means for interiorly locking the sections against displacement in the 20 grouped position, said means being adapted to be released through impact of the nose of the shell with an object and means for scattering the released sections.

9. A toy shell comprising butt and nose 25 ends, a guide shaft permanently connecting the ends, a gravity operated member slidably mounted on the shaft, shell sections grouped around the nose and butt ends and the sliding member and inclosing the side 30 of the shell and means coöperating with the sliding member to interiorly lock the sections closed in the displacement of the sliding member in one direction and to release them in the displacement of the sliding 35 member in the other direction.

10. A toy shell comprising butt and nose ends, a guide shaft permanently connecting the ends, a gravity operated member slidably mounted on the shaft, shell sections 40 grouped around the nose and butt ends and the sliding member and inclosing the side of the shell, means coöperating with the sliding member to interiorly lock the sections closed in the displacement of the sliding 45 member in one direction and to release them in the displacement of the sliding member in the other direction and means for scattering the sections upon the same becoming unlocked.

50. 11. A toy shell comprising nose and butt ends, a guide shaft permanently connecting the ends, a gravity operated member slidably mounted on the shaft, a plurality of head and butt sections grouped end to end 55 and forming the body of the shell and having their inner ends normally bearing on the sliding member and overlapped and their outer ends releasably engaged with the nose and butt ends respectively and locking means secured to the butt sections and adapted to be engaged by the shifting member to 60 lock the sections closed and upon the shifting member being shifted in a direction toward the butt end.

12. A toy shell comprising nose and butt 65 ends, a guide shaft permanently connecting the ends, a gravity operated member slidably mounted on the shaft, a plurality of head and butt sections grouped end to end and forming the body of the shell and having their inner ends normally bearing on the 70 sliding member and overlapped and their outer ends releasably engaged with the nose and butt ends respectively and springs permanently attached to the butt sections and 75 adapted to be engaged by the shifting member to lock all of the sections closed and upon the shifting member being shifted to the butt end, said springs being further designed to engage with the shaft and be 80 brought into tension when the sections are locked.

13. A toy shell comprising nose and butt ends, a guide shaft permanently connecting the ends together, a sliding member mounted on the shaft and provided with an extending cylindrical skirt directed toward the butt end, sets of nose and butt sections assembled around the shaft but clear of the same and with their inner ends meeting on 85 the sliding member and with the ends of the butt sections overlapping the ends of the nose sections and with their outer ends releasably mounted in the nose and butt sections and a lengthwise extending spring secured to each of the butt sections and having one end engaged with the guide shaft to effect a tension in the spring and the other end extending and inclining inwardly to allow the said end of the spring to pass inside the flange of the shifting member upon the shifting member being shifted toward the butt end of the shell. 90 95

14. An assembled sectional toy shell having the assembled sections locked and the locking effected in a manner such that the sections cannot be unlocked by exterior manipulation. 100

15. An assembled sectional interiorly locked toy shell adapted to be unlocked by impact with an object and in no other way. 110

16. An assembled sectional toy shell presenting a nose and butt end and provided interiorly with shifting means adapted to interiorly lock the sections against opening 115 upon the striking of the butt end of the shell against an object and to unlock and to release the sections upon striking of the nose end against an object.

17. In a toy shell the combination with a 120 guiding shaft and a shifting member slidably mounted on the shaft of a retarding spring carried by the shaft and engageable with the shifting member.

18. In a toy shell the combination with a 125 guiding shaft and a shifting member slidably mounted on the shaft of a retarding spring carried by the shaft and engageable with the

shifting member in a certain predetermined position of the sliding member on the shaft.

19. In a toy shell the combination with a guiding shaft and a shifting member embodying a disk like head slidably mounted on the shaft of a retarding spring countersunk in and secured to the shaft and extending lengthwise thereof and adapted to re-

tard the shifting member when brought into engagement with the spring.

Signed at Winnipeg, this 4 day of May 1917.
